CLAIM

The ornamental design for a hunting camera, as shown and described.

DESCRIPTION

FIG. 1 is a front elevational view of a hunting camera showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof; and,

FIG. 8 is a bottom, rear and left side perspective view thereof.

The broken lines and the lower opacity areas within the broken lines show portions of the hunting camera that form no part of the claimed invention.

1 Claim, 8 Drawing Sheets---
